UNITED STATES PATENT OFFICE.

WILLIS A. INGALLS, OF CLEVELAND, OHIO.

KNITTING-MACHINE.

1,121,251.

Specification of Letters Patent. Patented Dec. 15, 1914.

Application filed May 4, 1912. Serial No. 695,203.

To all whom it may concern:

Be it known that I, WILLIS A. INGALLS, a subject of George the Fifth, King of England, residing in Cleveland, Cuyahoga county, Ohio, have invented certain new and useful Improvements in Knitting-Machines; and I hereby declare the following to be a full, clear, and exact description of the same, such as will enable others skilled in the art to which it appertains to make and to use the same.

My invention relates to the mechanism for mounting and operating the needle in knitting machines. In these machines as heretofore made the needle and needle plate are subject to excessive friction and consequent wear and breakage, due to the manner in which the needles are mounted and actuated. The needles are mounted in slots in the needle plate or dial and the projecting shank of the needle actuated by cams suitably mounted and operated without support for the shank of the needle, except such as it receives from the sides of the slot in the dial or needle plate. In some machines the depth of the slot has been increased beyond the thickness of the needle so as to allow the side of the projecting shank of the needle to have bearing surface against the sides of the slots in the dial, while in other machines other devices have been used to give greater bearing surface to the sides of the needle to prevent the needle from yielding in the direction of the motion of the cam causing it to bind in its slot and shear off the shank of the needle.

The object of my invention is to so mount and operate the needle that the bearing surface thereof, and of the needle plate in which it is mounted, and also that part of the needle through which motion is imparted, (hereinafter referred to as its shank,) shall not be subjected to the wear and strain incident to the present method of operating needles.

My invention consists in the usual slotted or grooved needle plate, in which needles are mounted in the usual manner, and an auxiliary needle plate so mounted with reference to the needle plate proper that the outer end of the projecting shank of the needle is supported by corresponding slots or grooves in the auxiliary needle plate, and in this manner held rigidly against the actuating cam, thereby obviating the strain and

resulting friction and wear in the slot of the needle plate proper and overcoming the breaking of the needle. I accomplish this by dividing the cam plate into two parts and conveying motion to the needles in the manner hereinafter described.

The idea or conception of supporting the outer end of the shank of the needle and one method of embodying it are shown in my application for Letters Patent filed June 5, 1909, Serial No. 500,547, Letters Patent, No. 1,025,470, issued to me May 7, 1912, and the invention herein described, in addition to the central idea of supporting the outer end of the needle shank, shown in both applications, consists in the mechanism for imparting motion to the needle in that class of machines where the needle dial revolves and the cams are held stationary as distinguished from the former application wherein the needle plates are held stationary and motion is imparted to the needle by the movement of the cam plate and cams.

In the accompanying drawings, Figure 1 is a sectional side elevation. Fig. 2 is a view of the under side of the auxiliary needle plate, showing cams and a section of cam plate, taken from line II, II, Fig. 1. Fig. 3 is a developed sectional view of the vertical auxiliary cam plate, taken from line III, III Fig. 1, and showing cams and section of cam ring and annular ring or plate K. Figs. 4 and 5 show details of the horizontal and vertical needle plates, taken from lines IV, IV, and V, V, Fig. 1. Fig. 6 shows detail of rollers and support for conveying motion from the vertical to the horizontal needle plate, with fabric passing down between the rollers. Fig. 7 shows modified form of needle shank, such as may be used in my machine, but forms no part of my invention.

A is the frame of the machine.

B is the central vertical shaft mounted in the center and forming the axis of the machine.

C is the horizontal needle plate and D is the auxiliary horizontal needle plate.

E is the vertical cylindrical needle plate and F the auxiliary vertical needle plate.

The horizontal cam plate C is loosely mounted on the shaft B and is supported by the collar or flange b rigidly mounted on the shaft B and an annular ring b¹ resting on and securely fastened to the collar or

flange b^3 . The annular ring b^3 is rigidly attached to the horizontal needle plate C by screws b^4 . The auxiliary horizontal needle plate D is loosely mounted on the shaft B, resting on the hub of the needle plate C and secured thereto by screws c^1 . In the upper surface of the horizontal needle plate C are the slots c , (Figs. 1 and 4,) and in the lower surface of auxiliary needle plate D are the slots d (Figs. 1, 2 and 4,) and resting in the slots c are the needles I with their shanks i projecting into and adapted to engage the corresponding slots d in the needle plate D. Mounted in the needle plate C is the annular cam ring H, having teeth h^2 on its inner surface adapted to engage the teeth h^1 of the gear h. The shaft J passes vertically through the needle plate C with the pinion h rigidly attached to its upper end and the pinion j^1 rigidly attached to its lower end. The teeth j of the pinion j^1 are adapted to engage the inner toothed surface b^2 of the annular ring b^1 . Mounted on the upper side of the cam ring H are the cams h^3 secured thereto by the screws h^4 , the cams being adapted to extend outwardly between the needle plate C and the auxiliary needle plate D and force the shank i of the needle I outward. Mounted on the lower outer surface of the cam plate G are the cams g secured thereto by the screws g^1 , the cams being adapted to come in contact with the shank i of the needle I and force the needle inward. On the lower surface of the needle plate C is the projecting lug c^2 supporting the pin c^3 and roller c^4 mounted on the latter. The object of this roller and its supports is to convey motion to the needle plate C from the corresponding lug 40 and roller on the vertical cylindrical needle plate E.

The vertical cylindrical needle plate E and auxiliary needle plate F are mounted on the annular plate or ring K and rigidly secured thereto by the screws e , f , respectively. The annular ring or plate K is fitted in the inner and lower side of the frame A of the machine and adapted to revolve therein. It is held in place by the small annular ring k , by the screws k^1 , (Fig. 1) and has a toothed surface k^2 , adapted to engage the toothed surface of the pinion U hereinafter described. The outer surface of the cylindrical needle plate E is provided with slots or grooves e^1 (Figs. 1 and 5) adapted to receive the needles M, and the inner surface of the vertical needle plate F is provided with corresponding slots or grooves f^1 adapted to engage the outer end of the shank m of the needle M. Mounted on top of the inner side of the frame A is an annular ring N resting on the lug n and held rigidly in place by the screws n^1 . The annular ring N is toothed on its lower surface, the teeth n^2 being adapted to engage the

teeth of the pinion O. Mounted on the ring N is the cam plate P secured to N by the screws n^3 . The cams p are mounted on the inner surface of the top of the cam ring P by the screws p^1 , the cams being adapted to engage the shank m of the needle M and force the needle downward. Mounted between the needle plate E and the needle plate F is the cam ring Q having a toothed surface q adapted to engage the teeth r of the pinion R. The pinion R and the pinion O are rigidly mounted on the horizontal shaft S, which is in turn loosely mounted in the lower part of the needle plates E and F. The cams q^1 are mounted on the inner side of the cam Q by the screws q^2 , the cams being adapted to engage the shank m of the needle M and force the needle upward. The lug e^2 attached to the cam ring E supports a roller e^3 (Figs. 1 and 6) and the roller engages the corresponding roller c^4 revolving the needle plate C in unison with the needle plate E, the object of the rollers being to permit the finished work to pass down between them as will be readily understood by those skilled in the art. The shaft T is suitably mounted in the frame of the machine and is provided with loose and driving pulleys in the usual manner and has at its inner end a bevel gear U with toothed surface u of the gear engaging the toothed surface k^2 of the ring or plate K imparting motion to the latter.

The frame of the machine, A, is stationary and the central vertical shaft B being rigidly mounted therein is also stationary. Motion is imparted to the needles M through the revolving of the shaft T; its gear U to the annular plate or ring K, and thence to the vertical cylindrical needle plates E and F. The cam ring P is held stationary through its fastening to the frame A, while the cam ring Q is held stationary by means of the gear O, shaft S and gear R. As the needle plates E and F revolve the contact between the toothed surfaces of the pinion O and the lower side of the ring N revolve the shaft S and the pinion R, which in turn through the toothed surface of the lower side of the cam ring Q will maintain the position of the latter to correspond with the fixed position of the cam plate P. In this manner the needles M revolving with the needle plate E are brought into contact with the cams on the respective cam rings. The contact with the cams p forces the needles downward, while the contact with the cams q^1 , in turn, forces the needles upward. Motion is imparted to the needle plate C through the lug e^2 , the rollers e^3 and c^4 and the lug c^2 . The auxiliary needle plate D receives its motion through the needle plate C and screws c^1 . The cam plate G is firmly mounted on the stationary shaft "B.". The annular ring

*b*¹ remains stationary, being rigidly fastened to the stationary shaft B. The revolving of the needle plate C causes the pinion *j*, by reason of its contact with the toothed inner surface *b*² of the ring *b*¹, to revolve carrying with it the shaft J and the pinion *h*, which in turn, by contact with the toothed surface *h*² of the cam ring H causes the cams *h*³ to remain in a stationary position corresponding to the stationary position of the cams *g* on the cam plate G. The revolving of the needle plate therefore brings the shank *i* of the needles I into contact alternately with the cams *g* forcing the needles inward and the cam *h*³ forcing the needles outward and so completing the movement of the needles.

The mechanism herein described is particularly efficient in doing very fine work. 20 In this character of work the points of the needles are necessarily very close together, and when the slot and needle have become worn, even a slight twist in the needle is sufficient to cause the outer end of the needle 25 to come in contact with the opposing needle, breaking the needles. More frequently the material is cut by the contact of the needles, causing the machine to drop stitches and make holes in the garment and this results 30 in a great amount of waste. With my invention the needle is held rigidly in position and the point of the needle may come in very close proximity to the opposing needle without danger of coming in contact with 35 it, or near enough to it to injure the material.

From the foregoing specifications and drawings it will be readily understood that my invention may be applied to so-called flat 40 knitting machines as easily as it is to circular machines, and the necessary mechanical changes will readily suggest themselves to any person skilled in the art to which it appertains. It is also apparent that the 45 outer end of the shank of the needle need not be held in the particular manner or by the mechanism herein shown and that any desired means of supporting the outer end of the shank of the needle may be employed 50 and be within my invention. It is also apparent that any form of needle shank may be used in my invention, whether an integral part of the needle or separate therefrom.

55 Having described my invention, I claim:

1. In a circular knitting machine the combination of a rotary horizontal dial needle plate having slots or grooves for the reception of the needles, an auxiliary rotary 60 horizontal dial needle plate mounted opposite thereto and provided with slots or grooves corresponding to those of the needle plate, needles mounted in said needle plate and having shanks projecting into and adapted to engage the grooves of the aux-

iliary needle plate, a circular cam plate mounted above said needle plates with its outer edge projecting downward and adapted to support cams, cams secured to the circular cam plate and adapted to force the 70 shank of the needles inward, an annular cam ring mounted in the needle plate and adapted to support cams, cams secured to the annular cam ring and adapted to force the shank of the needles outward, and means 75 for holding the cam plate and cam ring in the same relative positions while the needle plate and auxiliary needle plate revolve for the purpose set forth.

2. In a circular knitting machine the combination of a vertical rotary cylindrical needle plate having in its outer surface vertical slots or grooves for the reception of needles, an auxiliary rotary cylindrical needle plate mounted outside of the needle plate 80 and having in its inner surface vertical slots or grooves corresponding to those in the needle plate, needles mounted in the slots or grooves of the cylinder and having shanks adapted to engage the slots or 85 grooves in said auxiliary cylinder, a cylindrical cam ring mounted outside the needle plates and adapted to support cams at its upper end, cams mounted on the upper end of said cam ring and adapted to force the 90 shank of the needles downward, an annular cam ring mounted between the needle plate and the auxiliary needle plate, cams mounted on said cam ring and adapted to force said cams upward and means for holding 95 said cam rings in the same relative position while the needle plate and auxiliary needle plate are revolved, for the purpose set forth.

3. In a circular knitting machine the combination of the rotary horizontal dial needle plate C having slots or grooves for the reception of the needles, an auxiliary rotary horizontal dial needle plate D mounted opposite thereto and provided with slots or 100 grooves corresponding to those of the needle plate, needles mounted in said needle plate and having shanks projecting into and adapted to engage the grooves of the auxiliary needle plate, a circular cam plate G 110 mounted above said needle plates with its outer edge projecting downward and adapted to support cams *g*, cams *g* secured to the circular cam plate G and adapted to force the shank of the needles inward, an 115 annular cam ring H mounted in the needle plate C, and adapted to support cams *h*³, cams *h*³ secured to the upper side of the annular cam ring and adapted to force the shank of the needles outward, the annular 120 ring *b*¹, with the toothed inner surface *b*², gears *h*¹ and *j*¹ mounted on a shaft J and adapted to respectively engage the toothed 125 surfaces of the annular ring *b*¹ and the annular cam ring H and to hold them in the 130

same relative position while the needle plates revolve, substantially as and for the purpose specified.

4. In a circular knitting machine the combination of the vertical rotary cylindrical needle plate E having in its outer surface vertical slots or grooves e^1 for the reception of needles, an auxiliary rotary cylindrical needle plate F mounted outside of the needle plate E and having in its inner surface vertical slots or grooves corresponding to those in the needle plate E, needles mounted in the slots or grooves of cylinder E and having shanks adapted to engage the slots or 10 grooves in cylinder F, a cylindrical cam ring P adapted to support at its upper end cams p, cams p mounted on the upper end of cam ring P and adapted to force the shank of the needles downward, an annular cam ring

Q mounted between the needle plates E and F, cams g^1 mounted on the inner surface of cam ring Q and adapted to force the shank of the needle upward, the annular ring N with its toothed surface n^2 , gears O and R rigidly mounted on shaft S and respectively 25 engaging the toothed surfaces of ring N and cam ring Q and adapted to hold them in the same relative position while the needle plates revolve, substantially as and for the purpose specified.

30 In witness whereof I hereunto set my hand at Cleveland, Ohio, this third day of May 1912.

WILLIS A. INGALLS.
